ATTORNEY.

UNITED STATES PATENT OFFICE.

WILLIAM SHARROCK, OF BEVERLY, MASSACHUSETTS.

PAINT-PAIL.

1,121,299.

Specification of Letters Patent. Patented Dec. 15, 1914.

Application filed February 13, 1914. Serial No. 818,470.

To all whom it may concern:

Be it known that I, WILLIAM SHARROCK, a British subject, and resident of Beverly, in the county of Essex and State of Massachusetts, have invented certain new and useful Improvements in Paint-Pails, of which the following is a full, clear, and exact description.

As well known, paint pails after use take on an internal lining or skin of dried paint so that if the pail is to be used for a paint of a different color it has been generally necessary to burn out the pail, a matter involving considerable time, close attention and expense. The burning process endangers the premises where it is carried out, and is prohibited by most insurance companies. Moreover, in the burning out of the old paint in the pail, there is liability of destroying the receptacle.

In carrying out the object of this invention, I provide internally of the paint pail, and additional to the side walls of the pail proper, with a plurality of closely related convolutions of impervious sheet material, the exposed one of which forms a protection for the remaining ones, enabling the user, as occasion may require, to remove the inner convolution or layer, leaving, then exposed, a fresh and clean layer of the pail lining for the manifest advantage. And incidental to the practice of this invention there is less adhesion of paint on the removable paint lining than there would be on the walls of the ordinary pail.

The invention is described in conjunction with the accompanying drawings and is set forth in the claims.

In the drawings: Figure 1 is a central vertical sectional view through a paint pail having the provisions of this invention. Fig. 2 is substantially a horizontal sectional view, as taken on line 2—2, Fig. 1. Fig. 3 is a view on a smaller scale showing a portion of the sheet material which forms the pail lining convolutions.

In the drawings, A represents the pail having the bail or handle *a* as usual, and *b* convolutions of impervious sheet material, the surface of each being in face contact against that of the next, but unattached each to the next throughout almost their entire areas. The circular layers comprised in the convolutions are however secured each to the next by any suitable adhesive having

fitness to the purpose, and along the narrow lines as represented at *f* in the drawings. The material forming the circular lining layers for the pail may advantageously be a hard paper treated to render it impervious to liquid, and the adhesive employed may be shellac. The said convolutions are preferably made with weakening lines, as indicated at *g* in the drawings, such, for instance, being produced by a line of perforations or scorings.

The paint pail as represented in Fig. 1 is made with an inwardly extending flange *h* around its upper edge and up to which the lining layers *b* extend; and said flange not only serves to prevent the displacement of the lining layers, but it also serves as a rib on which the paint brush may be wiped and prevents the entrance of paint between the lining layers. The number of convolutions or lining layers may be more or less,—the inclusion from 6 to 12 for a pail being entirely practicable. After use of the pail with a paint of one color or kind and it is desired to make use of the same pail for a paint of another color or kind, it is only necessary to strip off the convolution which had been exposed and on which a layer of skin or paint had accumulated, leaving the next convolution to form a fresh and clean exposed inner surface of the paint pail wall.

I claim:—

1. A paint pail having internally of, and additional to the side walls of the pail proper, a plurality of closely related convolutions of impervious sheet material, the exposed one of which forms a protection for the remaining ones, and said convolutions being for the greater portions of their areas, unattached each to the next. 90

2. A paint pail having an inwardly extending flange around its upper edge and provided internally of, and additional to the side walls of the pail proper, with a plurality of closely related convolutions of impervious sheet material, unattached each to the next for the greater portions of their areas, extending from the pail bottom to the under side of said flange. 100

3. A paint pail having internally of, and additional to the side walls of the pail proper, a plurality of closely related convolutions of impervious sheet material which are unattached each to the next, throughout the greater portions of their 110

areas, with means, however, for securing said convolutions one to another on small fractional parts only of their areas.

4. A paint pail having internally of, and
5 additional to a plurality of closely related convolutions of impervious sheet material, and means for securing said convolutions one to another on small fractional parts, only, of their areas,—said convolutions hav-

ing weakening lines extending from their 10 lower to their upper edges.

Signed by me at Springfield, Mass., in presence of two subscribing witnesses.

WILLIAM SHARROCK.
